UNITED STATES PATENT OFFICE.

VICTOR A. NELSON, OF PORTLAND, OREGON.

PISTON-RING REMOVER.

Application filed October 6, 1921. Serial No. 505,875.

To all whom it may concern:

Be it known that I, VICTOR A. NELSON, a citizen of the United States, and a resident of the city of Portland, county of Multnomah, and State of Oregon, have invented a certain new and useful Improvement in Piston-Ring Removers, of which the following is a specification.

This invention relates to piston ring removers of the type shown in the patent to Charles O. Hammontree and myself, dated April 20, 1920, No. 1,337,600, which is adapted to be used on a variety of different piston rings.

The deficiency which I experienced in the tool described by said patent is, that devices, or so called jaws, of the tool which function to engage the ends of the piston rings, so that the ends may be spread, would have to be of a form corresponding to the said ends; and in consequence at least two tools would be required—one for oblique ends another for square ends, which forms represent the standard types of piston rings at present in use.

The primary object of my invention is to provide a tool which is adapted to be used on either of said standard types of piston rings.

Another object of my invention is to provide a tool which is inexpensive to manufacture, in that it has but few parts, and the pieces may be stamped out of sheet metal.

The construction and use of my improved tool are shown in the accompanying drawings, in which:

Fig. 1 is a side view with the remover partially opening a piston ring and indicates the action when the ring is fully opened;

Fig. 2 is a cross sectional view of Fig. 1 on the line 2—2;

Fig. 3 is a bottom view of my tool;

Figs. 4, 5 and 6 are views showing the application of my tool to the different standard designs of piston rings;

Fig. 7 shows a sectional detail of construction;

Fig. 8 is a perspective view of the fixed jaw h ;

Fig. 9 is a cross sectional view on the same line as Fig. 7 and shows the relation of the different parts to each other; and

Fig. 10 is a perspective view of the removable jaw.

In Figs. 4, 5 and 6 are shown the different standard types of piston rings to which I

referred. Note that the piston rings shown in Figs. 4 and 5 have oblique ends, while the piston ring shown in Fig. 6 has square ends, that is each end has a rectangular jog 60 leaving a projecting lip; the lips of the two ends sliding by each other. I have designed this tool so that it will open all of the standard rings with the same jaw. I do this by placing the projecting fingers h^2 and a^2 65 slightly below the longitudinal center line of the body d . This allows the finger h^2 to slip by the projecting lip x in Fig. 6 and to seat firmly against the rectangular jog y as shown in the same figure. This feature will 70 not interfere with the proper operating of oblique end rings as the lips h^1 and a^1 prevent transverse movement.

Another big advantage of my present invention is that it can be manufactured very 75 cheaply. All of the parts are made from sheet metal and can be stamped and formed by simple machinery and the only assembling will be to drive one rivet. This will enable to compete in price with other similar products.

The movable jaw a is connected to the handle b by means of the rivet c and this whole assembly is movably connected to the body d . The body d is made up of a handle 85 e , a slot f , an offset g , a fixed jaw h composed of side lips h^1 , and a finger h^2 , all of which are stamped from a single piece of material.

The movable jaw a is also constructed with side lips a^1 , and a projecting finger a^2 . 90 The handle b is made with a depression i which is as deep as the thickness of the body d , as shown in Fig. 9, and thus eliminates the necessity of a separate guide plate. The off-set g brings the movable jaw to a position 95 in the same plane as the fixed jaw h .

The operation of this piston ring remover is approximately the same as the type shown in the patent issued to Charles O. Hammontree and myself dated April 20, 1920, Number 1,337,600. It is roughly as follows:

When an operator desires to remove a piston ring from its seat on the piston or desires to insert a ring in position on the piston he adjusts the tool so that the fingers a^2 105 and h^2 are pressed against each other. These fingers can then be inserted in the gap between the ends of the ring and the side flanges a , and b ; then slip on either side of ring to prevent transverse movement. The handles 110 e and b are then drawn together and the ring is then expanded and can be slipped over the

shoulder of the piston and the ring will resume its original shape and the tool can be released as soon as the contracting pressure on the handles is removed.

5 I claim:

1. In a tool for removing piston rings two connected members one of which is relatively slideable lengthwise on the other, each member being provided with a jaw for engaging one end of the piston ring, and each jaw comprising parallel spaced flanges and a pin-like shoulder located between said flanges barring one end of the channel between the flanges.

10 2. The tool described in claim 1 distinguished in that the said pin-like shoulders are aligned with each other and located nearer one side of the jaw channels for the purpose specified.

3. A tool for removing piston rings comprising a body-piece having a longitudinally extending slot cut out intermediate its ends, a companion piece seated on the body piece, having a portion thereof pressed out to form an elongated lug adapted to bear in said slot, 25 and a jaw affixed on said lug on the under side of the body-piece, thereby slidably connecting the said pieces, the jaw comprising parallel spaced flanges and a pin-like shoulder located between said flanges and barring one end of the channel between the latter, the body piece being provided with a jaw also comprising parallel spaced flanges and a pin-like shoulder located there-between, barring one end of the channel between the 30 flanges, and both pieces being provided with handles.

VICTOR A. NELSON.
